(57) **CLAIM**

The ornamental design for a bracelet convertible to wrist restraint as shown and described.

DESCRIPTION

FIG. 1 is a top view of the claimed design in a first configuration;

FIG. 2 is a bottom view of the claimed design in the first configuration;

FIG. 3 is a top view of the claimed design in a second configuration; and,

FIG. 4 is a bottom view of the claimed design in the second configuration.

The ornamental design that is claimed is shown in solid lines in the figures. Broken lines formed by equal or substantially equal length dashes show unclaimed portions of the design and form no part of the claimed design. Broken lines formed of unequal length dashes (i.e., dash-dot) show boundaries between claimed and unclaimed portions of the design. The design is shown having symbolic breaks, but the portions shown between break lines form no part of the claimed design.
